UNITED STATES PATENT OFFICE.

SPENCER OTIS, OF CHICAGO, ILLINOIS

DUMP-CAR.

1,089,493.

Specification of Letters Patent. Patented Mar. 10, 1914.

Application filed October 26, 1905. Serial No. 284,558.

To all whom it may concern:

Be it known that I, SPENCER OTIS, a citizen of the United States, residing in Chicago, county of Cook, and State of Illinois, 5 have invented certain new and useful Improvements in Dump-Cars, of which the following is a specification.

My invention relates to that class of dump cars having dumping doors and door operating mechanism supported in the transverse members of the car frame beneath the doors.

It relates further to the shaft and gear mechanism for operating the dumping doors and the construction of the end sills, whereby 15 by the gear mechanism for operating such shafts may be mounted beneath and outside of the inner face of the end sills.

It relates further to the construction and manner of mounting the side stakes upon 20 the transverse members of the car frame, including the body bolsters and intermediate transverse beams, and to the construction of such body bolsters and transverse beams.

The principal object of my invention is to 25 provide a simple, economical and efficient dump car.

Further objects are to provide a dump car with suitable mechanism for operating the dumping doors, comprising shafts mounted 30 beneath the doors in the transverse members of the car frame, and to provide suitable end sills for enabling the gear mechanism for operating such shafts to be mounted beneath and outside of the inner faces of such end sills and adapted to 35 enable the operating shafts connected with such gears to be mounted outside of the end frames of the car.

A further object is to provide suitable side 40 stakes and transverse members so constructed as to enable the web portions of the side stakes to be secured directly to the transverse members, and to provide suitable transverse hinge plates for supporting the 45 hinged sides of the dumping doors.

Other and further objects of the invention will appear from an examination of the drawings and the following description and claims.

50 The invention consists in the features, combinations and details of construction hereinafter described and claimed.

In the accompanying drawings Figure 1 is a transverse elevation of a car constructed 55 in accordance with my improvements, showing an end view of the portion of the car

to the right of the center of the figure, the portion to the left of the center line of the figure being shown in sectional elevation, taken on line 1 of Fig. 2 looking in the direction of the arrow; Fig. 2 a central sectional elevation of a portion of the car, taken on line 2 of Fig. 1 looking in the direction of the arrow; Fig. 3 a skeleton plan view of the portion of the bottom framework shown in Fig. 2; and Fig. 4 a detail perspective view, showing the construction of the side stakes and the manner of mounting them upon the transverse beams.

In constructing a car in accordance with 70 my improvements, I provide a car frame formed of side frames *a* and end frames *b*, the end frames being provided with stakes *c* mounted on the outside thereof and secured to the top plates of the end sills hereinafter 75 described. These side stakes are mounted upon the inner sides of the side frames over the transverse members of the bottom framework hereinafter described, and are formed of tapered web portions *d*. The outer upright sides or edges of the stakes are provided with vertical flanges *e* and the inner edges with inclined flanges *f*, which extend from top to bottom of the stakes at right angles to the main web portions. The upper 80 ends of the stakes are connected by channels 61 having their flanges directed outwardly and the lower ends of the stakes are similarly connected by channels 18. The channels 61 and 18 are connected by diagonal 85 members 60, which are secured to their inner faces. Planks 62 are secured to the outer faces of the stakes between said channels 61 and 18. The diagonal members 60 are constructed of flat plates, which lie against the 90 inner faces of the planks and are secured thereto as well as to the channels. The structure described forms a side truss capable of carrying the weight from the center and end parts of the car to the bolsters and the type of truss is such that the diagonal 95 members 60 are subjected to tensile strains only, thereby rendering it possible to construct them of flat unflanged metal plates. The construction of the diagonal members of 100 such flat plates avoids restricting the interior width of the car as would be done by the use of flanged members, and such members will be necessary if the truss were of a form imposing compressive strains upon the diagonal members. The truss is of the inverted queen-post type and the diagonal members 105 110

slope downwardly away from the adjacent points of support, that is, the bolsters. By this means I am enabled to carry the weight of the car upon the side trusses without the use of bulky trusses, which would restrict the interior dimensions of the car. When constructed according to my invention and provided with side trusses in the form above described, the center sill serves merely to take the buffing and draft strains and is supported from the bolsters, the load being transmitted to the bolsters by the side trusses and not by the center sill. A bottom frame is provided, having longitudinal center sills, formed preferably of channel irons, and each consisting of a central section *g* and end sections *h*. The end sections of the center sills have vertical web portions *i* of greater thickness than the web portions *j* of the central sections.

Body bolsters are mounted over car trucks of any ordinary and well known type and having supporting wheels *k*. The body bolsters are each formed of a pair of side plates *l* which extend transversely from side to side of the car, being of greater depth at their central portions than at their ends, as shown in Fig. 1. A top plate *m*, which forms the tension member, extends from end to end of the bolster and laterally beyond the outer faces of the side plates, being secured thereto by means of angles *n*, and a bottom plate *o* extends longitudinally of the bolster between the side plates near the lower edges thereof and is secured to the side plates by means of inner angle irons *p*. A plurality of vertical transverse plates *q* are mounted near the longitudinal center of each of the body bolsters, and secured to the side members by means of vertical angle irons *r*. These plates provide the necessary resistance to the vertical thrusts or strains upon the central bearings *s*. Upper lateral gusset plates *t* are secured to the opposite side plates by means of angle irons *u*, and bottom filler plates *v* are mounted on opposite sides of the body bolsters over the laterally projecting portions of bottom gusset plates *w*—which extend laterally beyond the side plates at the longitudinal central portion of the bolster—and are secured to the bottom flanges of the longitudinal center sills already described. Angle irons *y* have vertical flanged portions *z*, which extend inside of the side plates of the bolster and are provided with horizontal laterally extending flange portions extending between the bottom gusset plate and the lower edges of the side plates, as shown in Fig. 2. The central sections of the longitudinal center sills are connected with the side plates of the body bolsters by means of vertical connecting angles *3*, and the end sections of such sills are secured to the opposite sides of the body

bolsters by means of similar vertical angle members *4*. Transverse beams are mounted upon the longitudinal sills at suitable intervals, formed of vertical web portions *5*, which are secured to the longitudinal sills by means of angle irons *6*, forming bottom flanges for such transverse beams. Top angle irons *7* and *8* form upper lateral flange portions of the transverse beams, and the angle irons *8* are bent outwardly at their opposite ends, forming a space between them and the vertical web portions of the transverse beams, into which extend the depending web portions *9* of the side stakes, which are mounted upon the ends of such transverse beams. The vertical web portions of the side stakes and transverse beams are secured together by means of suitable rivets, as shown in Fig. 4.

Hinge plates *10* support the hinged sides of the doors. These plates extend transversely over the center sills from door to door and are provided with bottom angles *11*, by means of which their lower edges are secured in position. The hinge plates adjacent to the body bolsters and end sills are secured to the top gusset plates which extend over the center sills, and those mounted near the transverse beams—or centrally of the car—are secured directly to the top flanges of the center sills, as shown in Fig. 2. These hinge plates are provided with top flanges *12*, and the central floor plank *13* is laid thereon. Hinge members *14* are mounted upon opposite sides of the vertical web portions of such plates at the opposite ends thereof, so as to form supports for the hinge members *15* which are secured to the dumping bottom sections or doors *16*, such hinge members being connected by means of pivot pins *17*.

The dumping doors extend longitudinally on opposite sides of the car between the transverse members of the car frame, and are adapted to swing upward to closed position so as to form bottom portions, as shown in Fig. 1, and downward to inclined open dumping positions. The inner edges of the doors extend beneath the side edges of the center floor boards *13*, and their outer edges swing up into engagement with the bottom flanges of channel irons *18* which form the bottom members of the side frames and are above the floor level. These channel irons are secured to the lower ends of the side stakes, which, in turn, are secured to the body bolsters by means of angle irons *19*, as shown in Fig. 1.

My improved mechanism for operating the dumping doors comprises rotatable door-operating shafts *20*, which extend on opposite sides of its longitudinal center of the car beneath the dumping doors. These shafts are journaled in the transverse members of

- the car frame, which include the body bolsters and transverse beams already described. Reciprocatory shafts 21 extend parallel with these door-operating shafts beneath the outer 65
- 5 swinging portions of the dumping bottom sections or doors and are slidably supported by the transverse members of the car frame, being mounted upon inclined transverse tracks 22, the upper inclined surfaces of which extend 70
- 10 tend upward and outward at an incline transversely of the car. The track members are secured to the body bolsters and intermediate transverse beams—adjacent to the opposite ends of each of the dumping doors.
- 15 The door-operating shafts are each provided at suitable intervals with cranks 23, operatively connected with reciprocatory shafts by means of link members 24. The door-operating crank shafts are mounted a 75
- 20 sufficient distance inward from the outer swinging sides of the doors and inward from the reciprocatory shafts, so that the movement of the outer swinging ends of the cranks to raised position will be as near as 80
- 25 practicable in line with the direction of movement of the reciprocatory shafts with which such cranks are connected. In other words, the path of movement of the swinging ends of the cranks 23 when moving the 85
- 30 doors to closed position is upward and outward and, as near as possible, in line with the inclined surface portion of the supporting track member 22, and therefore as near as possible back of and in line with the path 90
- 35 of movement of the reciprocatory shafts operated thereby. End sills are provided which are so constructed as to permit the gears of the door-operating shafts to be mounted beneath and outside of the inner 95
- 40 face of the end sills in the desired position.
- The principal member or main body portion of each of the end sills is formed of a channel beam 25 having top and bottom flanges 26 and 27, both of which extend longitudinally from end to end of the sill without interruption or curvature. The flanges of the channel beam extend outward endwise of the car, and vertical angular gusset plates 26' are secured to and extend downward below 100
- 45 the lower edge of the channel beam so as to form a suitable support for the draw-bar shank. These vertical gusset plates are a sufficient distance apart to form a space beneath and at the center of the channel 105
- 50 beam member adapted to permit the draw-bar shank to be mounted beneath the lower flange of the channel beam, and a draw-bar supporting member 28 of angle iron is secured to the lower portions of the vertical 110
- 55 gusset plates and extends across the space therebetween. These gusset plates have laterally or rearwardly extending vertical flanges 29, which are secured to the inner 115
- 60 sides of the center sills by means of suitable rivets, and these rearward laterally extending flange portions are provided with upwardly projecting portions 30, which extend to the upper edge of the channel beam member forming a support for the rear portion of a top plate 31. The top plate is mounted upon the top of the channel beam member and extends over the laterally or rearwardly projecting flanges of the vertical gusset plates. Connecting angles 32 serve to connect the top plate with the upwardly projecting portions 30, and connecting angles 32 are secured to the top plate and the bottom of the end stakes by means of suitable rivets, so as to form an efficient support for the end frames. 120
- A horizontal gusset plate 34 extends over the longitudinal center sills on a plane below the end sill top plate, being secured to the top flanges of the longitudinal sills by means of suitable rivets, and an angle iron brace 35 is mounted upon such horizontal gusset plate and extends longitudinally of the end sill back of its main body portion and back of the rear edge of the top plate over the center sills and then obliquely beneath the top plate, being secured at its opposite ends to the longitudinally extending portions of the vertical gusset plate members and to the channel beam member. By this arrangement a space is provided beneath the top plate of the end sill adapted to permit gear mechanism for operating the dumping doors to be mounted beneath and outside of the inner face of the end sill or inner edge of its top plate member. Each 125
- 130 of the door-operating shafts 20 is provided with a gear wheel 36 mounted beneath one of the end sills, and a worm 37 is mounted in toothed engagement with each of such gear wheels and provided with a vertical hand wheel shaft 38, which extends upward through the end sill and on the outside of the end frame, being provided with a hand wheel 39 mounted at its upper end in a suitable bearing 40. The worms and worm 135
- 140 wheels are thus beneath the end sills and out of the way of the material to be handled, so that they are shielded by the end sills which extend over them in all directions. 145
- I claim:
1. In a car, a hinged dumping door, inclined tracks upon the door and upon the frame of the car, a reciprocatory shaft co-acting with said tracks, a rotary shaft for operating said reciprocatory shaft, said rotary shaft being located beneath the car and between the reciprocatory shaft and the center of the car, and connections between the rotary shaft and the reciprocatory shaft. 150
  2. In a car, a door, inclined tracks upon the door and upon the frame of the car, a reciprocatory shaft co-acting with said 155

tracks, and a rotary shaft for operating said reciprocatory shaft, said rotary shaft being located beneath the car and between the reciprocatory shaft and the center of the car.

3. In a car of the class described, a door, an inclined track on the under side of the door, an inclined track on the frame of the car, a reciprocatory shaft co-acting with 10 said tracks, a rotary shaft provided with a crank, and a link connecting said crank to the reciprocatory shaft for actuating the latter, the path of movement of the crank being substantially in alinement with the 15 lower track when the reciprocatory shaft is moving on said track.

4. In a car of the class described, a swinging door, co-acting inclined surfaces and a member operating between said surfaces for 20 actuating said door, and a power shaft located beneath the door and connected to said member.

5. In a car, an end sill comprising a vertical member extending continuously 25 throughout the width of the car, a reinforcing member spaced from the vertical member at its central portion and attached thereto at its end portions, and door operating mechanism located between the vertical 30 member and the reinforcing member.

6. In a car, an end sill comprising a vertical member, a horizontal top plate, a reinforcing member spaced from the vertical member at its central portion and secured 35 thereto at its end portions, and gearing beneath the top plate and between the vertical member and the reinforcing member.

7. In a car, a transverse beam comprising 40 a web portion and an angle member forming a flange on said web portion, and side stakes extending between said web portion and the angle member.

8. In a car, a transverse beam comprising 45 a web and an angle member, said web and angle member contacting at their central portions and being spaced apart at the ends, and side stakes extending between the end portions of the web and angle member.

9. In a car, a transverse beam consisting 50 of a web and an angle member secured thereto at its central portion and spaced therefrom at the ends, and a side stake having a web secured between the angle member and the web of the transverse member 55 and also secured to the top of the angle member.

10. In a car, a transverse beam comprising 60 a web and angle members secured thereto, said angle members forming flanges at the top of the web and one of said angle members being spaced from the web at its end portions, and side stakes secured between the web and the angle member which is spaced therefrom.

11. In a car of the class described, the 65 combination of a car frame provided with longitudinal sill mechanism, a central floor portion mounted over such longitudinal sill mechanism, dumping doors mounted on opposite sides of the longitudinal center of 70 the car, supporting plates extending transversely of the car beneath such central floor portion for supporting it, and dumping door hinges secured to such transverse supporting plates and to the dumping doors. 75

12. In a railway car, a body bolster, comprising side plates extending transversely of the car from side to side thereof, a top plate extending from end to end of the bolster, inner angle members securing the top 80 plate to the side plates, a bottom plate between the side plates, inner angle members securing the bottom plate to the side plates, and vertical transverse plates mounted within the bolster adjacent the longitudinal center thereof and secured to the side members. 85

13. In a railway car, a body bolster comprising side plates extending transversely of the car from side to side thereof, a top 90 plate extending from end to end of the body bolster and secured to the side plates, a bottom plate between the side plates and secured to the side plates, and upper gusset plates below the upper edges of the side 95 plates and secured to the side plates.

14. In a railway car, a body bolster comprising side plates extending transversely of the car from side to side thereof, a top 100 plate extending from end to end of the body bolster and secured to the side plates, a bottom plate between the side plates and secured to the side plates, upper gusset plates below the upper edges of the side plates and secured to the side plates, and lower 105 gusset plates secured to the lower edges of the side plates.

15. In a car of the class described, the combination of a body bolster provided with upright side plates, a top plate connecting 110 the upper portions of such side plates, a bottom plate mounted between the side plates near the lower edges thereof and provided with depending flanges, and angle irons having upright flanges mounted between the depending flanges of such bottom plate and having lateral flanges extending outward beneath the depending flanges of 115 such bottom plate.

16. In a car of the class described, the 120 combination of a body bolster provided with upright side plates having a space therebetween, upright filler plates extending transversely across such space and secured to the inner sides of such side plates, a top 125 plate connecting the upper portions of the side plates, a bottom plate mounted between the lower portions of the side plates and

- having depending flanges flush with the lower edges of such plates, angle iron members provided with upright flanges secured to such bottom plate and side plates and 5 having transverse flanges extending outward beyond the side plates, and a gusset plate mounted beneath such angle iron members and extending transversely of the bolster beyond the side plates.
- 10 17. The combination with a beam comprising two members, of a stake having a channel section, the web thereof extending down between the said members.
- 15 18. The combination with a beam comprising two members, of a stake having a channel section, the web thereof extending down between the said members, and the flanges thereof having shoulders above the members.
- 20 19. The combination with a beam comprising two members, of a stake having a channel section, the web thereof extending down between the said members, and means for attaching the stake to the top of the beam.
- 25 20. In a car, a center sill, cross members, bolsters, side trusses resting on said bolsters, said side trusses comprising channel shaped side stakes extending upwardly from and secured to said cross members, flanged metal chords secured to the outside of said stakes near the top and bottom thereof, planks secured to said stakes between said chords, and metallic diagonal members between said 30 stakes and secured to said chords and planks, said diagonal members sloping downwardly from the adjacent bolsters.
- 35 21. In a car, a center sill, cross members, bolsters, side trusses resting on said bolsters, 40 said side trusses comprising side stakes secured to and extending upwardly from said cross members, top and bottom channel iron chords secured to the outer faces of said side stakes near their upper and lower ends, planks secured to the outer faces of said 45 stakes between said chords, and flat metallic diagonal members secured to the inner faces of said chords and said planks, said diagonal members sloping downwardly from the adjacent bolsters.
- 50 22. In a car, a center sill, cross members, bolsters, side trusses resting on said bolsters, said side trusses comprising side stakes secured to and extending upwardly from said cross members, top and bottom iron chords secured to the outer faces of said side stakes near their upper and lower ends, and flat metallic diagonal members secured to the inner faces of said chords and said planks, said diagonal members sloping downwardly from the adjacent bolsters.
- 55 23. A railway car having trussed sides, each comprising an upper compression member of channel form, a lower tension member of channel form, struts of channel form, and diagonal tension members between said upper and lower members.
- 60 24. A railway car having trussed sides, each comprising an upper compression member of channel form, a lower tension member of channel form, and struts of channel form each having one flange secured to the webs of both said compression and tension members.
- 65 25. A railway car having trussed sides, each comprising an upper compression member of channel form, a lower tension member of channel form, struts of channel form each having one flange secured to the webs of both said compression and tension members, and a bolster, the webs of said struts being secured to said bolster.
- 70 26. In a car of the class described, a center sill, transverse sill and side stake, said transverse sill comprising a central web, and strengthening bars fixed along its upper edge, said bars being supported at the extremity of the central web and fixed to opposite sides of the side stake.
